D-TOP

Filed Feb. 28, 1927

INVENTOR

Winthrop Withington

BY Franklin Seagrave
ATTORNEY.

UNITED STATES PATENT OFFICE.

WINTHROP WITTINGTON, OF CLEVELAND, OHIO.

D TOP.

Application filed February 28, 1927. Serial No. 171,512.

My invention relates to that type of handles commonly known as "D-tops", which are suitable for various tools, such as shovels, spades, forks, and the like.

5 An object of the present invention is to provide a handle of this general character, comprising means for suitably securing a hand grip to the wood shaft of an implement, and which may be formed of sheet metal inexpensively produced by stamping and forming operations.

Another object of my invention is to provide a D-top made from a single integral sheet metal stamping which will be capable of 15 being readily affixed to an implement shaft and which will form a relatively non-yielding connection between the hand grip and the shaft.

Another object of my invention is to provide an improved metallic D-top capable of 20 being formed from sheet metal, wherein the portions subjected to bending or breaking stresses are reinforced substantially commensurable to the stresses which must be resisted by the D-top portions in use.

Other objects of my invention and the invention itself will become apparent as the description of an embodiment thereof, illustrated herein, progresses.

30 In the drawings:—

Fig. 1 is an elevational view of an embodiment of my invention affixed to the handle end of an implement shaft;

Fig. 2 is a side elevational view of the D-top of Fig. 1, the handle shaft end being omitted in this view;

Fig. 3 is a section taken on the line 3—3 of Fig. 2;

Fig. 4 is a bottom plan view of the D-top 40 of the foregoing figures, omitting a showing of the implement shaft end;

Figs. 5, 6, 7 and 8 are sectional views taken on the lines 5—5, 6—6, 7—7, and 8—8, respectively, of Fig. 1.

45 Referring now to the different figures of drawing, in all of which like parts are designated by like reference characters, at 1 I show an implement hand grip of substantially conventional form, adapted to be secured, as 50 illustrated in Fig. 1, to an end of an implement

shaft 2 by means of the D-top grip support 3. The D-top grip support is formed from a single sheet of sheet metal formed, as shown, so as to have a pair of grip-supporting forks 4 and 5, and a generally tubular shank portion 6, the ends of the forks being formed, as shown at 7 and 8, so as to provide opposing cup recesses to receive the reduced ends of the grip 1. The grip-receiving recessed ends of the forks 4 and 5 are centrally perforated, as 60 shown at 9 and 10, and a bolt 11 is projected through the openings 9 and 10 to support the grip 1, through the longitudinal axial bore of which the bolt extends. The ends of the bolt are headed over, as shown at 12, and retain the forks in their relative positions and provide for the secure clamping of the grip by the recessed fork ends. From the end walls of the grip-receiving recesses 7 and 8, pointed projections of the material of the 70 walls extend inwardly, as shown at 13, and these projections extend into the wood or other like material of the grips to prevent relative rotation of the grip upon the bolt.

It has, in the past, been found difficult 75 to secure the properties of rigidity and strength in a D-top for handles formed from a single piece of sheet metal, and various expedients have heretofore been resorted to in order to accomplish as near as might be possible, according to the means adopted, these 80 properties.

In my former Patent No. 1,585,222, dated May 18, 1926, I disclose a metallic D-top structure wherein, in order to form the sheet metal 85 in such a way as to secure rigidity of the grip-supporting forks thereof, and to provide for implement shaft embracing portions thereof, I found it necessary to provide notches, or arcuate slots, at the lateral portions where junction is made between the forks and the shaft-embracing parts. Although handles made in accordance with my said former patent have been used extensively, and have proven successful in use, the 90 present application is for a form of D-top which presents features of improvement over the structure of my said former patent, comprising such a disposition of the sheet metal thereof as will make a stronger connection be- 100

tween the grip-supporting forks and the implement shaft-embracing portions. This I accomplish by so forming the D-top that the necessity for any abrupt bends in the forming operations is entirely avoided, and the material of the forks and the material of the shaft-embracing parts comprising a junction of metallic portions involving a gradual bend or change of direction of the metallic strip and a projection of superfluous portions of the metal at certain portions in order to provide additional stress-resisting strength at such portions.

More specifically, the D-top of my present invention, comprises a lowermost pair of substantially semi-cylindrical tubular arms 14 and 15, which are bent downwardly until the relative positions, shown in Figs. 3 and 4, are had, whereby an implement shaft 2 may be snugly embraced between the arms, aligned pairs of perforations 16 and 17 permitting headed bolts, or rivets such as 18, to penetrate the handle shaft and to rigidly clamp the D-top shank portions 14 and 15 thereto. The forks 4 and 5 are of arcuate shape, as indicated by the views shown in the figures of drawings 5, 6 and 7, taken respectively of the lines of section 5-5, 6-6 and 7-7, of Fig. 1, and it will be seen, by reference to these drawings, that, progressively nearer and nearer the shank portions 14 and 15, the forks are of channel form of continuously increasing depth, and that, in the lower portions of the forks adjacent the shanks, longitudinal ribs 19 and 20 project from the upper surfaces thereof increasing the depth "d" of the concavity, Fig. 6, from that indicated at "d", Fig. 5; each of the ribs 19 and 20 also define, by their inner concave surfaces, a channel 21 which is of gradually increased depth from its uppermost portion to the lower end portion of the channel.

The result of both of these effects is to accomplish a maximum depth of arch "d" on the line of section illustrated in Fig. 7, and that the fork material, starting with a relatively flat portion at 22 adjacent the grip 1, is arched progressively more and more until adjacent the shank portions 14 and 15 the side portions of the forks become re-entrant, that is, are inturned in portions 23, being again reversely folded in portions 24 which become, in their lower portions, a part of the edges 25 of the semi-cylindrical shank elements 14 and 15. By virtue of the disposition of the sheet metal in the portions comprising the implement shaft-embracing elements and the lowermost portions of the forks, a substantially T-shaped tubular construction is evolved, the transverse elements of which are upturned to support the handle grip 1, being progressively of unrolled form as the handle grip-supporting ends of the forks are approached. The portion 26 of the sheet metal material, disposed immediately

above the implement shaft end and between the ribs 19 and 20, is nearly flat, being preferably slightly transversely arched, as shown in the view of the line of section 8-8 of Fig. 1, illustrated in Fig. 8.

The grip-supporting ends of the forks 4 and 5 are formed by pressing the material of the forks at their ends into substantially cup-shaped form, and the grip ends are, as illustrated, preferably reduced to fit within the side walls of the fork cups thereby provided.

It will be observed that the laterally disposed joining portions 27, Fig. 1, extend from the substantially semi-cylindrical shank portions 14 and 15 from a point considerably below the upper end 29 of the implement shaft to give the forks, in portions toward their ends, the form of a substantially gradually unrolled tube.

This construction, while permitting metal of considerable thickness to be employed, the form of the D-top providing for the taking up of all of the metal which otherwise would be subjected to a contracting stress, yet has a very considerable resistance to the stresses imposed upon the D-top incidental to the use of the D-top when applied to an implement shaft. At the same time, the manufacturing problem, which was solved in one way in my said former patent, is herein solved in a different way, and to the end that a D-top of increased strength for a given thickness of sheet metal is provided.

Having thus described my invention in a specific embodiment, I am aware that numerous and extensive departures may be made from the embodiment herein illustrated and described, but without departing from the spirit of my invention.

I claim:

1. A D-top adaptable for application to an end of an implement shaft, comprising a U-shaped metallic strip, curved transversely substantially throughout its length to form an outer channel of progressively increased depth proceeding from its end portions towards its intermediate portion of greatest depth the side arms thereof being of continuously curved cross sectional form between their ends and the said intermediate portion, a pair of laterally disposed tool handle embracing arms, each approximately semi-cylindrical in form integrally depending from each side of the most deeply channelled intermediate portion of the strip, the lateral portions of the strip being inturned in portions adjacent its said intermediate portion to integrally join the lateral portions of the arms with the lateral edges of the strip to effect a junction of the arms and strip throughout substantially the entire width of the upper portions of the arms.

2. A D-top adaptable for application to an end of an implement shaft, comprising a U-

shaped metallic strip, channelled transversely substantially throughout its length to form an outer channel of progressively increased depth proceeding from its end portions towards its intermediate portion of greatest depth the side arms thereof being of continuously curved cross sectional form between their ends and the said intermediate portion, a pair of laterally disposed tool handle 5 bracing arms, each approximately semi-cylindrical in form integrally depending from each side of the most deeply channelled intermediate portion of the strip, the lateral portions of the strip being inturned only in portions adjacent its said intermediate portion to integrally join the lateral portions of the arms with the lateral edges of the strip to effect a junction of the arms and strip throughout substantially the entire width of the upper portions 10 of the arms, and aligned openings through the arms adapted to receive a handle securing bolt or the like for holding the arms closely about the end of the implement or the like.

3. A D-top adaptable for application to an end of an implement shaft, comprising a U-shaped metallic strip, curved transversely substantially throughout its length to form an outer channel of progressively increased depth proceeding from its end portions towards its intermediate portion of greatest depth the side arms thereof being of continuously curved cross sectional form between their ends and the said intermediate portion, 20 a pair of laterally disposed tool handle embracing arms, each approximately semi-cylindrical in form integrally depending from each side of the most deeply channelled intermediate portion of the strip, the lateral portions 25 of the strip being inturned in portions adjacent its said intermediate portion to integrally join the lateral portions of the arms with the lateral edges of the strip to effect a junction of the arms and strip throughout substantially the entire width of the upper portions 30 of the arms, the strip being flattened on its surface disposed remote to the arms to approximately conform with the end of the implement shaft projected within the arms.

4. A D-top adaptable for application to an end of an implement shaft, comprising a U-shaped metallic strip, curved transversely substantially throughout its length to form an outer channel of progressively increased depth proceeding from its end portions towards its intermediate portion of greatest depth, the side arms thereof being of continuously curved cross sectional form between 55 its ends and the said intermediate portion, a pair of laterally disposed tool handle embracing arms, each approximately semi-cylindrical in form integrally depending from each side of the most deeply channelled intermediate 60 portion of the strip, and oppositely dis-

posed handle receiving sockets formed integrally with the arms at their ends.

5. A D-top adaptable for application to an end of an implement shaft, comprising a U-shaped metallic strip, curved transversely 70 substantially throughout its length to form an outer channel of progressively increased depth proceeding from its end portions towards its intermediate portion of greatest depth, the side arms thereof being of continuously 75 curved cross sectional form between its ends and the said intermediate portion, a pair of laterally disposed tool handle embracing arms, each approximately semi-cylindrical in form integrally depending from each side 80 of the most deeply channelled intermediate portion of the strip, and oppositely disposed handle receiving sockets formed integrally with the arms at their ends, said sockets being substantially cup-shaped in form, the side 85 arms formed to project their depressed channel portions toward each other within the planes of the spaced socket and walls.

6. A D-top adaptable for application to an end of an implement shaft, comprising a U- 90 shaped metallic strip, channelled transversely including an intermediate portion having a channel of greatest depth, the side arms thereof being of channelled form between their ends and the said intermediate portion, a pair 95 of laterally disposed tool handle embracing arms, each approximately semi-cylindrical in form integrally depending from each side of the most deeply channelled intermediate portion of the strip, the lateral portions of the strip disposed adjacent its said intermediate portion being inturned to integrally join the lateral portions of the side arms with the lateral edges of the cylindrical arms, and comprising a junction of the cylindrical arms and 100 said side arms throughout substantially the entire width of the upper portions of the cylindrical arms, and aligned openings through the cylindrical arms adapted to receive a handle 105 securing bolt or the like for holding the arms closely about the end of the implement or the like, the joining portions of strip and arms having lateral edges extending divergently from the arm edges.

In testimony whereof I hereunto affix my 115 signature this 24th day of February, 1927.

WINTHROP WITHINGTON.
